UNITED STATES PATENT OFFICE.

CHARLES W. REYNOLDS, OF NEW YORK, N. Y., ASSIGNOR TO PARA TIRE CO. OF NEW YORK, INC., OF NEW YORK, N. Y., A CORPORATION OF NEW YORK.

DESIGN FOR AN AUTOMOBILE-TIRE.

51,736.

Specification for Design.

Patented Feb. 5, 1918.

Application filed December 3, 1917. Serial No. 205,275. Term of patent 14 years.

To all whom it may concern:

Be it known that I, CHARLES W. REYNOLDS, a citizen of the United States, residing in the city of New York, county of New York and State of New York, have invented a new, original, and ornamental Design for Automobile-Tires, as illustrated in the accompanying drawing.

The drawing herewith illustrates in per-

spective view a portion of an automobile tire in which my novel design is embodied.

What I claim is:

The ornamental design for an automobile tire, as shown.

CHARLES W. REYNOLDS.

Witnesses:

GEORGE L. BLUME,
F. GRAVES.
